US00D447053B1

(12) **United States Design Patent** (10) Patent No.: **US D447,053 S**
 Chagnon et al. (45) Date of Patent: ** Aug. 28, 2001

(54) **CONTAINER**

(75) Inventors: **Nichole M. Chagnon**, Whitefish Bay; **Joseph Perushek**; **Charles Austen Angell**, both of Madison, all of WI (US)

(73) Assignee: **S. C. Johnson Home Storage, Inc.**, Racine, WI (US)

(**) Term: **14 Years**

(21) Appl. No.: **29/127,401**

(22) Filed: **Aug. 4, 2000**

(51) LOC (7) Cl. **09-03**

(52) U.S. Cl. **D9/428**

(58) Field of Search D9/428, 429, 430, D9/431, 418, 424; D7/601, 602, 608, 629, 641; 229/4.5, 5.5, 905, 932, 400-406; 206/769, 770, 776, 777, 457, 303; 220/4.21, 4.24, 4.25

3 copies of photographs of Container Disclosed to S. C. Johnson & Son, Inc. by Keith Catlin, Mar. 1997 in 9 inch, 15 inch and 21 inch sizes.

Primary Examiner—Prabhakar Deshmukh

(57) **CLAIM**

The ornamental design for a container, as shown and described.

DESCRIPTION

FIG. 1 is a front perspective view from above and to one side of the container showing the new design.

FIG. 2 is a top view of the container of FIG. 1.

FIG. 3 is a bottom view of the container of FIG. 1;

FIG. 4 is an elevational view of the container of FIG. 1; and,

FIG. 5 is a second elevational view, rotated 90° from the first

elevational view, of the container of FIG. 1.

1 Claim, 3 Drawing Sheets
